UNITED STATES PATENT OFFICE

160,011

GLOBE FOR LIGHTING FIXTURES

Paul C. Perrin, Pittsburgh, Pa., assignor to Porcelier Manufacturing Company, Greensburg, Pa., a corporation of Pennsylvania

Application June 20, 1949, Serial No. 3,410

Term of patent 3½ years

(Cl. D48—15)

To all whom it may concern:

Be it known that I, Paul C. Perrin, a citizen of the United States, residing in Pittsburgh, in the county of Allegheny, and State of Pennsylvania, have invented a new, original, and ornamental Design for Globe for Lighting Fixtures, of which the following is a specification, reference being had to the accompanying drawing forming part hereof, in which:

Fig. 1 is a front elevational view of a globe for lighting fixtures, showing my new design;

Fig. 2 is a side elevational view thereof;

Fig. 3 is a top view;

Fig. 4 is a fragmentary elevational view of the side opposite to that shown in Fig. 2; and

Fig. 5 is a transverse section in the plane of line 5—5 of Fig. 2.

I claim:

The ornamental design for a globe for lighting fixtures, as shown.

PAUL C. PERRIN.
